ROBERT E. MCFARLAND, OF LA GRANGE, ILLINOIS, ASSIGNOR TO WESTERN ELECTRIC COMPANY, INCORPORATED, OF NEW YORK, N. Y., A CORPORATION OF NEW YORK

MATERIAL SLITTING DEVICE

Application filed September 10, 1930. Serial No. 480,839.

This invention relates to material slitting devices, and more particularly to a device for splitting multi-conductor cables into separate individually insulated conductors.

5 In the manufacture of insulated electrical conductors, particularly rubber covered conductors, it has been found economical, in some instances, to first produce a multi-conductor cable by extruding a common integral covering upon a plurality of conductors disposed in spaced parallel relationship and then slitting the covering material lengthwise intermediate the conductors to produce a plurality of separate individually insulated conductors. The insulation between the conductors may be formed of a reduced cross section to facilitate the subsequent slitting operation.

An object of the present invention is to 20 provide a simple and efficient material slitting device.

One embodiment of the invention contemplates the provision of a device for splitting a double conductor rubber covered cable into 25 separate individually insulated conductors, wherein the cable is advanced between peripherally opposed circular knives secured to spaced rotatable arbors between spring pressed rollers rotatably carried upon the arbors and arranged to accommodate irregularities in the rubber covering and constantly maintain the conductors properly aligned with respect to the knives.

A more complete understanding of the invention will be had from the following detailed description when read in conjunction with the accompanying drawing, in which

Fig. 1 is a plan view of a device embodying features of the invention;

40 Fig. 2 is a side elevational view thereof, and

Fig. 3 is a vertical section, partly in elevation, on line 3—3 of Fig. 2.

Referring now to the drawing, wherein like 45 reference numerals designate the same parts in the several views, it will be observed that a pair of peripherally opposed circular knives or cutters 10—10 are secured to spaced parallel shafts or arbors 11—11, rotatably journaled at each end in spaced supporting standards

12—12. A plurality of guide rollers 14, 14 are rotatably carried upon the arbors 11, one on either side of each of the knives 10. The rollers 14 are yieldably pressed toward the knives by compression springs 16, 16 interposed between the rollers and collars 17—17 fixed to the arbors 11. The collars 17 also serve to prevent longitudinal displacement of the arbors.

The rollers 14 are provided with peripheral 60 grooves 18 which conform to the contour of and cooperate to accommodate a cable 19 comprising a pair of spaced parallel conductors 20—20 having a common integral covering 21 of rubber or rubber composition, the 65 covering material being formed of reduced cross section intermediate the conductors, as indicated at 22, to facilitate the splitting operation.

In the operation of the device, a double conductor cable 19 is drawn from a supply source (not shown) between the spring pressed rollers 14 which compensate for irregularities in the rubber covering and thereby cooperate to constantly maintain the cable properly centered with respect to the knives 10, so that the covering material 21 is evenly and uniformly slit along the reduced section 22 thereof. In this manner the insulating covering of the separated individual conductors are maintained substantially uniform in cross section 75 throughout the length of the conductors.

It will be understood that the embodiment of the invention herein illustrated and described represents only one useful form of the 80 invention which is capable of other applications within the scope of the appended claims.

What is claimed is:

1. In a material slitting device, material slitting means, and a plurality of cooperating 90 guide rollers co-axial therewith for yieldably engaging the material to center it with respect to the slitting means.

2. In a material slitting device, a supporting shaft, a pair of freely rotatable rollers 95 carried thereby for guiding the material, and a material slitting element mounted upon the shaft between the rollers.

3. In a material slitting device, a supporting shaft, a pair of material engaging rollers 100

carried thereby, a material slitting element mounted upon the shaft between the rollers, and means yieldably pressing the rollers toward each other.

5. In a material slitting device, a plurality of spaced shafts, a circular cutter carried upon each of the shafts, means for maintaining the cutters in peripheral alignment, and means on said shafts for yieldably engaging the material to center it with respect to the cutters.

10. In a material slitting device, a pair of peripherally opposed circular cutters, and freely rotatable rollers co-axial therewith for guiding the material between the cutters.

11. In a material slitting device, a pair of peripherally opposed circular cutters, rollers co-axial therewith for guiding the material between the cutters, and means yieldably pressing the rollers toward the cutters.

12. In a cable splitting device, a plurality of peripherally opposed spring pressed rollers having peripheral grooves cooperating to provide an adjustable guide passage for the cable, and a pair of peripherally opposed circular cutters co-axial with the rollers for splitting the cable as it passes between the rollers.

13. In a cable splitting device, a plurality of spaced parallel arbors, a pair of rollers rotatably carried by each of the arbors and having peripheral grooves cooperating to provide a guide passage for a cable, means for yieldably pressing the rollers into engagement with the cable, and a circular cutter carried upon each of the arbors intermediate the rollers, the cutters being peripherally opposed and arranged to split the cable as it passes between the rollers.

In witness whereof, I hereunto subscribe my name this 25th day of August A. D., 1930.

ROBERT E. McFARLAND.
